ATTORNEY

UNITED STATES PATENT OFFICE.

HENRY E. REEVE, OF NEW YORK, N. Y.

ELECTRIC SWITCH.

933,489.

Specification of Letters Patent. Patented Sept. 7, 1909.

Application filed May 12, 1908, Serial No. 432,385. Renewed June 17, 1909. Serial No. 502,800.

To all whom it may concern:

Be it known that I, HENRY E. REEVE, a citizen of the United States, residing at New York, in the county of Kings and State of New York, have invented certain new and useful Improvements in Electric Switches, of which the following is a specification.

My invention relates to improvements in electric switches.

10 It is particularly designed for use in incandescent lamp sockets, but it will be obvious that its use is not so limited.

The object of the invention is to provide a simple and reliable mechanism which is 15 durable, will enable the operator to break a circuit quickly without arcing and which can be manufactured economically.

The invention consists of improvements, the principles of which are illustrated in the 20 accompanying single sheet of drawings.

Figure 1, is a vertical section of mechanism embodying the improvements of my invention, the parts of the switch being in the open or "off" position. Fig. 2, is a similar 25 view, the parts of the switch being in the closed or "on" position. Fig. 3, is a plan view of the parts of the switch. Fig. 4, is a perspective view of the switch frame. Fig. 5, is a perspective view of the movable contact member. Fig. 6, is a plan view of the 30 operating cam. Fig. 7, is a sectional view similar to Fig. 2 of a construction embodying modifications of details of the invention. Fig. 8, is a perspective view of the catch 35 shown in Fig. 7. Fig. 9 is a fragmentary plan view of the contact arm shown in Fig. 7.

The invention is illustrated as embodied in a lamp socket in which the screw threaded sleeve 1 for receiving the lamp (not shown) 40 is attached in suitable manner to a porcelain block 2 which forms one-half of the insulating base. The other half of the base is indicated at 3. Two halves of the base are secured together in any suitable manner as is 45 customary in the art and are recessed to receive the switch mechanism.

The switch frame may be conveniently 50 formed of sheet metal stamped or formed as illustrated in Fig. 4. The spring member 4 whose tip is adapted to contact with the bottom of the sleeve 1, is anchored or supported between a depending shoulder 5 of the switch frame and an abutment formed by a pin or bar 6 which passes through 55 perforations 7, 7 in the sides 8, 8 of the switch frame. This bar 6 is preferably an integral

part of the base 9 of a binding post having a clamp nut 10 for securing one of the conductors to the switch. Electric connection will thus be direct from the binding post to 60 the switch arm 4.

The two-armed cam 11 which serves to move the spring member 4 is fixed on shaft 12 and may thus be turned by a button 13 in either direction. This cam shaft 12 preferably rests on the bottom of the switch frame and is held in place by the porcelain block 2. One side of the frame is notched as at 14 to receive the shaft. At the bottom of the tongue 41 is shoulder 42 coacting with the 70 cam 11. The width and location of the cam are such that it never comes under the contact tip of the spring member 4, but is always beneath the tongue 41. The spring catch 15 is anchored or held between the 75 walls 16 and 17 of the switch frame, the shoulder 18 preventing displacement. The tongue 41 is integral with the switch arm and coacts with the catch 15. When the cam is rotated from the position shown in Fig. 1, it engages the shoulder 42 and thus raises the contact arm so that the tip of the catch snaps under the tongue 41 to support the contact arm in the "closed" position, (see Fig. 2). The catch has a shoulder 19 adapted to be engaged by the cam so that when the cam is rotated from the position shown in Fig. 2 the catch is raised and disengaged from the tongue 41. The contact arm thus released, snaps quickly down opening the 80 circuit abruptly.

In the form shown in Fig. 7, the switch arm 4' is anchored in a different manner. The rear end passes beneath the pin 27 and bears against the flange 28, which is formed by turning one side 29 of the switch frame. 95 The sides of the switch frame are slotted as at 30 to receive the anchor pin 27. The catch 15' is anchored in a manner similar to that before described except that the wall 31 is not closed down to the same extent as the wall 17 in Fig. 4. In this form the tip of the switch arm lies between the flanges 20, 20 of the catch. When the cam is turned 100 from the dotted position to the full line position of Fig. 7 to close the circuit, one arm engages the switch arm 4', and raises it until the catch snaps down with the shoulders 24, 24 beneath the edges 32, 32 of the switch arm as shown in full lines. For this purpose the parts are so proportioned that the cam lifts the contact arm 4 a little higher 110

than the position shown so that the catch is free to snap under. When the cam is released the contact arm presses down on the shoulders 24, 24. When it is desired to retract the switch arm 4', the cam 11 is turned until one arm engages the boss 25 of the catch and forces it back so as to disengage the catch shoulders 24, 24 from beneath the edges 32, 32 of the switch arm, which immediately snaps out of contact with the sleeve and takes the position of Fig. 7. While it is possible to use straight members in the switch like the arm 4' in Fig. 7, I prefer to form shoulders like 42 and 19 in Figs. 1 and 2 as they permit a much greater range of movement of the members. It is particularly desirable to form a shoulder like 42 on the contact arm but I prefer to also have a shoulder like 19 on the catch. In both forms the points of engagements of the cam with the catch and switch arm, and the point of engagement of the catch with the switch arm being located close together, the movements are positive and quick. The advantages of the construction herein described and particularly the preferred form illustrated in Figs. 1 to 6 inclusive will be apparent to those acquainted with this art, particularly as regards simplicity of construction, durability and positiveness of action.

What I claim is:

1. In an electric switch, a frame, a spring contact member carried thereby, a spring catch and a rotatable cam adapted to engage the contact member to move it into "closed" position and adapted to move the catch to release the contact member.
2. In an electric switch, a frame having side flanges with openings, a binding post base extending through said openings, a spring contact member having one end electrically engaging said base, a rotatable cam for moving said contact member in one direction and a catch for holding said member in its "closed" position.
3. In an electric switch, a frame having a shoulder, a spring contact arm engaging said shoulder, a transverse bar serving as an abutment for said contact arm, a rotatable cam for operating said arm and a catch for said arm also operated by said cam.
4. In an electric switch, a frame, a spring contact arm carried thereby and having a shoulder, a spring catch for supporting said arm and a cam for engaging said shoulder to move said switch arm in one direction and for moving said catch to release said arm.
5. In an electric switch, a spring contact arm, an operating cam, a spring catch having a part for supporting said arm in the "closed" position and having another part adapted to be engaged by said cam to release said arm.
6. In an electric switch, a spring contact

arm having a shoulder, a spring catch for 65 said arm said catch having a shoulder and a cam for engaging the shoulder of said arm to close the circuit and also engaging the shoulder of said catch for releasing the same to open the circuit.

7. In an electric switch, a spring contact arm having a shoulder and a tongue, a catch for supporting the tongue of said arm and a cam for engaging said shoulder to move said arm and permit said catch to engage beneath said tongue.

8. In an electric switch, a spring contact arm having a tongue, a spring catch having a portion to engage said tongue to support the arm and a cam for operating said members.

9. In an electric switch, two insulating blocks having recesses, a switch-frame located in said recesses and having side flanges, a spring contact arm and a spring catch carried by said frame between said flanges, a cam for operating said arm and catch, a shaft for said cam supported by said frame and held in place between said blocks.

10. An electric switch comprising a frame 90 having a downwardly inclined wall with an upwardly inclined extension, a spring catch having a loop held between said walls, a contact arm coöperating with said catch and a cam for operating said arm and catch.

11. An electric switch comprising a frame having a downwardly inclined wall with an upwardly inclined extension, a spring catch having a loop between said walls, a shoulder on one wall for holding said loop, a contact arm coöperating with said catch and a cam for operating said arm and catch.

12. In an electric switch, a frame having an abutment and a shoulder, a cam, a spring contact arm pressing toward said cam and having a loop held between said shoulder and said abutment, and a catch for said arm operable by said cam.

13. In an electric switch, a spring contact member having a projecting tongue, a catch 110 adapted to coact with said tongue and support said contact member and means coacting with said contact member at the base of said tongue to move the contact member and close the circuit.

14. In an electric switch, a spring contact member having a tongue at one side, a spring catch having its tip adapted to coact with said tongue and means coacting with said contact member and with said catch for moving said contact member to close the circuit and for moving said catch to release said contact member and open the circuit.

HENRY E. REEVE.
